(57) **CLAIM**

I claim the ornamental design for an axle nut cap, as shown and described.

DESCRIPTION

FIG. 1 is an isometric view of my new axle nut cap;

FIG. 2 is a top plan view thereof;

FIG. 3 is a front elevation thereof;

FIG. 4 is a bottom plan view thereof; and,

FIG. 5 is an auxiliary elevation view taken along the line 5—5 in FIG. 2 thereof.
